UNITED STATES PATENT OFFICE.

EDWARD AUGUSTUS DENNIN, OF TROY, NEW YORK.

BRUSH.

1,375,681.

Specification of Letters Patent. Patented Apr. 26, 1921.

Application filed October 15, 1919. Serial No. 330,694.

To all whom it may concern:

Be it known that I, EDWARD AUGUSTUS DENNIN, a citizen of the United States, residing at Troy, in the county of Rensselaer 5 and State of New York, have invented certain new and useful Improvements in Brushes, of which the following is a specification.

This invention relates to brushes, and an 10 object of the invention is to provide a compact brush structure particularly well adapted to be carried about in the pocket of the user or in a traveling bag or other receptacle used by travelers. The said brush comprising 15 a back or brush head carrier which is concavo-convex and has detachably connected thereto the bristle carrying head which is constructed of flexible material so that it may be flexed to fit within the back, 20 a cover being provided for connection with the back or brush head carrier to entirely inclose the bristles of the brush, thus preventing the collection of dust, dirt or other matter by the bristles when not in use and 25 avoiding danger of garments becoming soiled by bristles which may have become oily from use.

A further object of the invention is to provide means which will permit the ready 30 connection or disconnection of the brush head carrier and the cover in such manner as to prevent accidental movement of one relative to the other and to facilitate disconnection by action of the thumb of the 35 user.

A further object of the invention is to provide a brush structure which comprises a concavo-convexly curved back into which the bristle carrying resilient head is flexed 40 when not in use and which back is provided with a finger opening in the center thereof, through which the user's finger is inserted to extend the bristle carrying body of the brush outwardly in opposed convexed relation to the carrying back to render the brush operative.

A further object of this invention is to provide a bristle carrying body or head for the brush which is constructed of a sheet 50 of resilient rubber provided with a plurality of openings therein through which the bristles are inserted and which sheet of resilient rubber has a layer or sheet of rubber placed over the inner surface thereof and vulcanized thereto for securely retaining the bris-

ties in place and preventing them from working loose during the use of the brush.

Other objects of the invention will appear in the following detailed description taken in connection with the accompanying 60 drawing, forming a part of this specification, and in which drawing:

Figure 1 is a perspective view of the improved brush.

Fig. 2 is a longitudinal section of the 65 brush in a collapsed position.

Fig. 3 is a cross section through the brush collapsed.

Fig. 4 is a longitudinal section through 70 the brush extended.

Fig. 5 is a cross section through the brush extended.

Fig. 6 is an inner plan of the cover illustrating the mirror carried thereby, and

Fig. 7 is a detail perspective view illustrating 75 the manner of attaching the bristles to the bristle carrying body of the brush.

Referring more particularly to the drawings, the improved brush structure includes 80 the separable housing parts 10 and 11, the former of which constitutes the back or main body portion and is substantially concavo-convexly curved, presenting its convexed surface outwardly. It has an annular inturned edge 12 which serves to retain a 85 bristle carrying body 13 of the brush in operative relation thereto. This bristle carrying body 13 comprises a layer 14 of flexible rubber which is provided with a plurality of openings 15 through which the 90 bristles 16 of the brush extend. The bristles 16 may be bent to lie across a portion of the inner surface of the layer 14 of pliable rubber as illustrated in Fig. 7 and extend downwardly through adjacent openings if desired and if long enough, or if 95 they are not long enough to be extended through two openings, their inner ends may be bent merely to overlie or engage the inner surface of the strip 14. A strip or 100 layer 17 of substantially raw rubber is placed over the inner surface of the layer 14 and is vulcanized for securely anchoring the bristles 16 to the body 14. In vulcanizing the strip of rubber 17 to the sheet or 105 layer 14 some of the rubber of the sheet 17 will enter the openings 15 in the sheet 14 securely sealing the openings and locking or fastening the bristles securely in place.

As clearly shown in the drawings the 110

- bristle carrying body 13 is oval in shape and when in operative position bulges outwardly from the brush back 10, presenting a convexed surface opposite to the convexed surface of the body 10. However, this bristle carrying body of the brush is adapted to be flexed to lie within the brush back 10 as shown in Figs. 2 and 3 of the drawings at which time the curvature of the body 13 conforms to the curvature of the brush back or part 10 of the brush structure. A relatively thin sheet 19 of celluloid or analogous material may be placed between the confronting faces of the brush body 13 and the part 10 of the brush structure and when the former is flexed inwardly, this plate 19 lies in facial abutment with the inner concaved surface of the part 10. This part or brush carrying back 10 is provided with a finger opening 20 centrally therein, through which a finger is inserted to extend the flexible back 13 of the brush or to force it out of the carrying back 10 into an operative position.
- The part or section 11 of the brush structure forms a cover for the bristles 16 when the brush is collapsed as clearly shown in Figs. 2 and 3 of the drawings and is preferably oval in shape or shaped to conform to the shape of the brush carrying back 10. Its major portion is preferably flat and has an annular upstanding edge portion or flange 20' formed thereon, and when the brush is flexed inwardly and the two parts thereof are connected, at which time the brush is in condition to be carried about in the pocket or hand luggage of the user, the edge portion of this flange 20' engages the brush carrying back 10 at its girth, or at the junction of the inturned flange 12 with the concavo-convex back of the brush carrying part or section 10. The flange 20' has lips 22 and 23 formed thereon at opposite points substantially at the minor axis of the cover, which engage over the outer convex surfaces of the section 10 to connect the sections 10 and 11 for preventing accidental relative movement thereof. The lip 23 is provided with a cut out portion 24 forming a finger or thumb receiving recess or opening which will enable the user to get a firm grip on the section 10 beneath the flange 12 for disconnecting the sections 10 and 11. In connecting the parts 10 and 11 of the brush after the brush carrying body 13 has been flexed into the part 10, the part 10 is tilted at an acute angle with respect to the part 11 and one edge thereof is inserted against the lip 22 after which the brush back is forced against this lip and downwardly until the lip 23 engages over a portion of the convexed surface of the part 10 which lip 23 co-operates with the lip 22 to securely hold the parts connected.
- A glass 25, preferably a mirror may be placed within the part 11 with its silvered side inwardly, so that when the parts 10 and 11 are disconnected, this cover part 11 may be held in one hand of the user permitting use of the mirror while brushing his hair with the brush part. The mirror 25 is preferably beveled or reduced in thickness at its edge portion and is confined in the cover part 11 by a ring 26 of any suitable material which engages the inner surface of the flange 20'. The flange being curved slightly extending inwardly toward the center of the cover part at its outer edge, as clearly shown in Fig. 2 of the drawings, the ring 26 will be confined in place for securely holding the mirror 25 in place. This ring 26 is preferably constructed of any suitable material of slight elasticity so that when the mirror 25 is placed within the cover part, the ring may be sprung into place.
- While in the drawings, a military brush is illustrated it is to be understood that the principle of the present brush structure may be applied to clothes brushes, hand brushes or any analogous type of brush without departing from the spirit of this invention.
- Changes in details may be made without departing from the spirit of this invention, but;
- I claim:
1. A brush comprising a concavo-convex carrying back, a flexible bristle carrying body of greater area than the opening of the cavity of said back connected thereto at its marginal portion to be flexed to lie in the cavity of the carrying back or extend to curve out of the back oppositely to the curvature thereof. 100
  2. A brush comprising a concavo-convex carrying back, provided with a finger opening, and a flexible bristle carrying body of greater area than the opening of the cavity of said back connected thereto at its marginal portion to be flexed to lie in the cavity of the carrying back, or to be forced to extend in oppositely opposed curved relation thereto by a finger inserted through said finger opening. 105
  3. A brush comprising a carrying back having a cavity at one face thereof, and a flexible bristle carrying body of greater area than the opening of said cavity and connected to said back at its marginal portion to be flexed to inherently maintain a position within the cavity of said back or to be extended to curve and inherently maintain a position out of the cavity of the back. 115
  4. A brush comprising a carrying back having a cavity at one face and a transverse finger opening leading from the other face to said cavity, and a flexible bristle carrying body of greater area than the opening of the cavity of the back, con- 120
  5. A brush comprising a carrying back having a cavity at one face and a transverse finger opening leading from the other face to said cavity, and a flexible bristle carrying body of greater area than the opening of the cavity of the back, con- 125
  6. A brush comprising a carrying back having a cavity at one face and a transverse finger opening leading from the other face to said cavity, and a flexible bristle carrying body of greater area than the opening of the cavity of the back, con- 130

nected thereto at its marginal portion and adapted to be flexed to lie in the cavity of said back, said bristle carrying body adapted to be flexed to extend out of said cavity 5 by a finger inserted through said finger opening.

5. In a brush, a carrying back having a cavity open at one face thereof, a flexible bristle carrying body of greater area than 10 the opening of said cavity in said back, connected thereto at its marginal portion to be flexed to inherently maintain a position within the cavity of the back when not in use, and to be projected therefrom 15 for use, and a cover detachably connected to said carrying back to close said cavity and house said bristle carrying body when lying within the cavity of the back.

6. A brush comprising a carrying back 20 having a cavity at one face and a transverse finger opening leading from the other side of the back to said cavity, a flexible bristle carrying body of greater area than the opening of said cavity, connected thereto 25 at its marginal portion and adapted to be flexed to lie within said carrying back, said bristle carrying body adapted to be flexed to extend out of said cavity by a finger inserted through said finger opening, and a 30 flexible plate positioned within said cavity of the carrying back between the facing surfaces of the carrying back and the bristle carrying body.

7. A brush comprising a concavo-convex 35 carrying back, a flexible bristle carrying body connected thereto and adapted to be flexed to inherently maintain a position within and conforming to the curvature of the back, and a flexible plate positioned be-

tween the facing surfaces of said bristle 40 carrying body and said back, said bristle carrying body adapted to be extended to curve out of the back and inherently maintain a position oppositely to the curvature thereof. 45

8. In a brush, a carrying back, and a bristle carrying body of flexible material carried thereby and adapted to inherently maintain a position within the back to house 50 said bristles in the back when not in use, said flexible bristle carrying back adapted to be extended to position the bristles carried thereby in operative position.

9. In a brush, a carrying back having a cavity at one face and provided with an 55 inturned annular flange at the margin of said cavity, and a flexible bristle carrying body of greater area than the opening of said cavity and engaged within said flange to connect the body to said carrying back, said 60 flexible body adapted to be flexed to inherently maintain a position within the cavity of the carrying back when not in use, or to be extended therefrom for use. 65

10. A brush comprising in combination, a carrying back having a cavity open at one face thereof, a flexible bristle carrying body carried by said body adapted to be flexed to extend from said cavity or lie therein when not in use, a cover detachably connected to said carrying body to close the cavity thereof when said bristle carrying body is within the cavity, and a glass carried by said cover at the inside thereof to confront and engage the bristles of said 70 75 bristle carrying body.

EDWARD AUGUSTUS DENNIN.
